(57) **CLAIM**

The ornamental design for a thermostat, as shown and described.

DESCRIPTION

FIG. 1 is a front view of one preferred embodiment of a thermostat in accordance with the invention;

FIG. 2 is a first side view of the thermostat shown in FIG. 1;

FIG. 3 is a second side view of the thermostat shown in FIG. 1;

FIG. 4 is a top view of the thermostat shown in FIG. 1;

FIG. 5 is a rear view of the thermostat shown in FIG. 1;

FIG. 6 is a bottom view of the thermostat shown in FIG. 1;

FIG. 7 is a first rear elevation of the thermostat shown in FIG. 1;

FIG. 8 is a first front elevation of the thermostat shown in FIG. 1;

FIG. 9 is a second front elevation of the thermostat shown in FIG. 1; and,

FIG. 10 is a second rear elevation of the thermostat shown in FIG. 1.
